UNITED STATES PATENT OFFICE.

PHILLIP HEAY, OF VANCOUVER, BRITISH COLUMBIA, CANADA.

BOILER.

Application filed January 5, 1922. Serial No. 527,188.

My invention relates to improvements in boilers, with more particular reference to those used in hot water heating systems, although my improvements may be applied to 5 steam boilers also, and the object of my invention is to provide a boiler of simple and strong construction in which the heating surface in relation to the water space and size of the boiler is very large so that it may be 10 constructed at a comparatively low cost and operated with great economy and efficiency.

I attain these objects by the construction illustrated in the accompanying drawings in which—

15 Fig. 1 is a longitudinal sectional elevation taken on the centre line of the boiler.

Fig. 2 is a cross sectional elevation taken on the line 2—2 of Fig. 1.

20 Fig. 3 is a sectional plan view taken on the line 3—3 of Fig. 1.

Fig. 4 is an outside end elevation of the boiler.

Similar figures of reference indicate similar parts throughout the several views.

25 In construction the boiler may be rectangular with square ends or any other approved design, although in its preferred form, as illustrated, the ends are semi-circular.

30 The lower portion which in height is approximately half the height of the complete boiler consists of an outer shell, indicated generally by the numeral 1, having the top plate 2, side plates 3 and 4, and the end plates 5 and 6, within which outer shell is arranged the firebox, indicated generally by the numeral 7, having the top plate 8, side plates 9 and 10, and end plates 11 and 12, the firebox being spaced from the outer shell so that

35 a lower water chamber 13 is provided between the firebox and the shell and which extends around the top, sides and ends of the firebox, the bottom of this water chamber being closed by a mud ring 14, all as shown in Figs. 1 and 2. The sides and ends of the firebox are stayed from the sides and ends of the outer shell by means of stays 15 and the front half of the top plate 8 of the firebox is stayed from the top plate 2 of the shell

40 by stays 16, while the rear half of the top plate 8 of the firebox is stayed from the top plate 2 of the shell by means of stay tubes 17, these stay tubes being pitched close together and preferably arranged in parallel rows, as 45 shown in Figs. 1, 2 and 3.

18 indicates an intermediate water cham-

ber disposed above and spaced from the lower outer shell 1, this water chamber being enclosed by spaced upper and lower plates 19 and 20 respectively, the side plates 21 and 22 and the plates 23 and 24 and being supported from the outer shell 1 by the side plates 25 and 26 and the end plates 27 and 28, which plates, besides supporting the water chamber, also form a shell to enclose the space between the chamber and the outer shell 1 so that a combustion chamber 29 is formed, as shown in Figs. 1 and 2. The front halves of the plates 19 and 20 are stayed from each other by means of stay 50 tubes 30 pitched close together and preferably arranged in parallel rows while the rear halves of the plates are stayed from each other by stays 31, and between the lower water chamber 13 and the intermediate 55 one 18 extend vertical water tubes 32 and 33, which water tubes are positioned adjacent the front and rear ends of the water chambers respectively and, extending through the combustion chamber 29, establish communication between them.

34 indicates an upper water chamber disposed above and spaced from the intermediate water chamber 18, this water chamber being enclosed by spaced upper and lower plates 35 and 36, the side plates 37 and 38, and end plates 39 and 40 and being supported from the intermediate chamber 18 by the side plates 41 and 42 and end plates 43 and 44, which plates, besides supporting the water chamber 34, also form a shell to enclose the space between this chamber and the intermediate one so that a combustion chamber or smoke chamber 45 is formed, as shown in Figs. 1 and 2. The upper and 60 lower plates of the water chamber 34 are stayed from each other by vertical stays 46 while the side plates 37 and 38 are stayed from each other by transverse stays 47, and communication is established between the 65 upper and intermediate water chambers respectively by vertical water tubes 48 and 49 positioned towards each side of the chambers and a short distance in front of the transverse axis of the boiler.

105 The rear end of the chamber 45 is provided with an opening 50 to which the lower end of a chimney 51 is connected and the firebox is provided with the usual door 52, bridge 53, and firegrate 54, below which is 110 arranged the ashpit 55 having the front opening 56.

It is not thought necessary to show or describe the various joints throughout the boiler in detail as it will be readily understood that these are in accordance with the best practice in boiler construction; it may be pointed out, however, that the design of the boiler is such that practically all the joints may be welded or riveted with the utmost facility.

- 10 In operation the flame, hot gases, and smoke from the firebox pass up through the rear stay tubes 17 into the rear end of the lower combustion chamber 29, travel forwardly therethrough to pass up through the front stay tubes 30 into the forward end of the upper combustion chamber 45, through which they travel rearwardly and pass out through the opening 50 into the chimney 51, as indicated by the arrows in Fig. 1.
- 15 With reference therefore to the lower water chamber it will be seen that the water therein is heated through a large area of heating surface formed by the area of the top, side and end plates forming the firebox and the combined peripheral area of the stay tubes 17 which pass through the water, to which area should be added that of the top plate of the shell 1, since this is heated by the heat passing through the combustion chamber 29, so that the total area of heating surface available for heating the water in the lower chamber 13 is very large in comparison with the amount of water contained in the chamber. This is also the case in the intermediate water chamber 18 the heating surface area available to heat the water therein being made up of the area of the lower plate 20 which is heated by the hot gases passing through the combustion chamber 29, the combined peripheral area of stay tubes 30 which pass through the water and are heated by the gases passing through them, and the area of the upper plate 19, which is heated by the gases as they pass through the upper combustion chamber 45 on their way to the chimney, the gases at the same time heating the lower plate 36 of the upper water chamber 34 and also the water tubes 48 and 49, the lower water tubes 32

and 33 being heated by the gases in the lower combustion chamber, from all of which it will be seen that the utmost use is made of the heat units between the firegrate and the chimney, thus ensuring great efficiency and economy in the operation of the boiler.

What I claim as my invention is:

A boiler comprising a fire box, a shell enclosing the fire box and spaced therefrom so as to provide a shallow water chamber above and at the sides of the fire box, a second shell superposed on the first shell, a second flat shallow water chamber superposed on the second shell and composed of spaced plates, the lower of which cooperates with the shell to provide a lower combustion chamber between the first and second water chambers, a third shell superposed on the second water chamber, a third water chamber superposed on the third shell composed of spaced plates, the lower of which cooperates with the adjacent shell to provide an upper combustion chamber which is positioned between the second and third water chamber, a plurality of vertical stay tubes extending through the first water chamber from the fire box to the lower combustion chamber on the rear side of the transverse axis of the boiler, a plurality of vertical stay tubes extending through the second water chamber from the lower combustion chamber to the upper combustion chamber on the front side of the transverse axis of the boiler, stay bolts arranged through the remaining portions of the two water chambers and also through all of the third water chamber, a tubular connection between the rear end of the first water chamber and the second water chamber, a tubular connection between the front ends of said first and second water chambers, and a pair of tubular connections between the second and third water chambers arranged on opposite side of the longitudinal axis of the boiler a short distance in front of its transverse axis.

In testimony whereof I affix my signature at the city of Vancouver, B. C., the 21st day of December, 1921.

PHILLIP HEAY.
